Alvin Rosenblatt
ATTORNEY.

UNITED STATES PATENT OFFICE

AUGUST COPPOLA, OF NEW YORK, N. Y.

SHADE ROLLER

Application filed July 5, 1928. Serial No. 290,329.

This invention relates to shade rollers.

Among the objects of the invention is to provide a device of the character described which shall be cheap to manufacture, comprise few and simple parts, permit quick assembly and shall yet be rugged in construction, and efficient and practical to a high degree.

Other objects of this invention will in part 10 be obvious and in part hereinafter pointed out.

The invention accordingly consists in the features of construction, combinations of elements, and arrangement of parts which will 15 be exemplified in the construction hereinafter described, and of which the scope of application will be indicated in the following claims.

Fig. 1 is a side elevation with parts broken 20 away, of a roller shade embodying the invention;

Fig. 2 is an end view of the roller with parts broken away to show the interior construction;

25 Fig. 3 is a partial cross-sectional view taken on line 3—3 of Fig. 2;

Fig. 4 is a front view of a blank from which one of the parts is formed;

Fig. 5 is a front view of the part formed 30 from the blank shown in Fig. 4;

Fig. 6 is a detail view showing the pawl assembly; and

Fig. 7 is a view of the pawl housing taken 35 from the interior of the roller.

Referring in detail to the drawing, 10 designates the shade roller embodying the invention which is here seen to comprise a tubular roller 11 preferably made of wood, mounting a curtain roll 12. Said roller is 40 formed with a closed end 13 and an open end 14 and is provided with means at both ends thereof for mounting the shade on a window frame (not shown). At the closed end 13, the mounting means comprises a cap member 15 snugly fitted over said end portion 13 and comprising an end wall 16 and a cylindrical portion 17. Said end wall 16 is apertured centrally thereof to receive a pin 18 driven into said end portion 13 of the roller. Said 50 pin 18 is preferably provided with a shoul-

der flange 19 adjacent the outer end thereof, abutting said end wall 16. The cap member 15 is preferably formed of stamped sheet metal and the end wall 16 thereof may be formed with prongs 20 punched into said end wall 13 to more firmly secure said cap to said roller. The outer end portion 21 of said pin 18 is adapted to be inserted in an ordinary bearing bracket in the window frame for mounting the roller, as is well known in the art. Where the frame is somewhat wider than the roller, the pin 18 may be withdrawn a short distance as required to lengthen the shade. It will be noted that when the pin is thus pulled, the shoulder 19 of said pin is necessarily removed from abutting relation with the cap member 15. In such position the prongs 20 prevent the cap member from becoming loose on the roller 11.

The means for mounting the roller 11 at 70 the open end 14, comprises a cap member 25 fitted over said open end. Said cap member 25 being formed with a cylindrical portion 26 and an end wall 27, spaced from the open end of the roller. The cylindrical portions 26 75 may be formed with an inwardly pressed outer edge portion 28 for firmly securing said cap to the roller 11.

A stamped, cup-shaped member 29 may be housed in the cap member 25 between the 80 spaced walls 26 and 14. Said member 29 comprises a cylindrical portion 30 contacting the inner surface of wall 27 of said cap 25, and an end wall 31 adjacent the roller end 14. Said end wall 31 may be punched to provide 85 diametrically spaced prongs 32 which are forced into the end portion 14 of the roller 11 to fix said member 29 thereto. The end wall 31 may be further stamped to provide diametrically spaced strap portions 33 abutting 90 said end portion for a purpose herein-after appearing, also stamped to provide a central bearing portion 34. A spindle 35 extends within the roller and is provided with a metal band 36 secured thereto at one end 95 thereof, the band 36 having a reduced portion 36a journaled in bearing 34. A flat cross-shaped member 37 complementary to pin 18, may be secured to said spindle 35, one end 38 of said member 37 being driven into the 100

left end of the spindle 35 (as seen in Fig. 3) and secured thereto by a pin 39. Said member 37, it will be noted, extends thru an enlarged opening 40 in the end wall 26 of cap member 25 and thru a suitable opening in the metallic band 36, and is provided with aligned projections 41 and a tongue or trunnion 42 which is engageable in the slot of an ordinary shade roller fixture to non-rotatably support said spindle 35.

The customary coil retrieving spring 43 surrounds the spindle and is secured thereto at one end 44 preferably by inserting the outer convolution 45 of said spring in a slit 46 cut in said end 44. The opposite end of the spring 43 is secured to the cup member 31, preferably by passing the outer convolution 47 thereof thru the opening formed by the strap member 33.

It will now be apparent that when the curtain 12 is lowered, the roller 11 is rotated against the tension of spring 43. Release of the curtain will permit the tensioned spring to again wind the curtain on the roller 11.

The roller shade 10 is provided with one way brake means 50 to prevent rewinding of the curtain 11 unless pulled down with sufficient speed to render said brake means inoperative. Said brake means 50 comprises a circular ratchet plate 51 mounted on member 37 between the projections 41 and the band 36. Said plate 51 is provided with diametrically spaced peripheral angular notches 52, each notch presenting a ramp portion 53 and an abutment wall 54. Said notches 52 are adapted to receive dogs or pawls 55 pivotally mounted, as hereinafter described, on a stamped plate 56 positioned within cup member 29 and adjacent end wall 26 of cap member 25. Said plate 56 may be formed from the blank shown in Fig. 4 which is seen to comprise four equally spaced extensions 57 and four projections 58, alternately spaced between said extensions 57. Said plate 56 is further provided with an enlarged opening 59 thru which the member 37 may extend. The projections 58 are bent at right angles to the plate 56, as seen in Fig. 5, and are formed with reduced end portions 59 received in suitable openings 60 formed in wall 31 of member 29. The projections 58 thus comprise shafts extending between plate 56 and wall 31 and supported by the latter. Said shafts 58 further provide means for securing said plate 56 against rotation relatively to said member 29. Four dogs 55 are provided and each is formed with an opening 61 at one end thereof for mounting said dogs on said shafts 58. It will now be apparent that by lowering the shade the roller may be rotated in a counter-clockwise direction looking at Fig. 2. During this movement the dogs simply slide over ramps 53. Upon release of the curtain the tensioned spring will tend to rotate the roller in an opposite direction. However, a dog

55 will engage stops 54 to prevent the shade from rewinding. When, however, the curtain is given a sudden jerk down, the roller rotates quickly and the dogs fly out radially due to centrifugal force. Sudden release of the curtain will now permit rewinding of the curtain since the dogs are out of engagement with the notches 52. During the rewinding of the curtain, centrifugal force due to rotation will continue to hold the dogs out of contact with stops 54.

The parts comprising the mounting and brake structure are made of metal stampings which may readily be assembled in a manner obvious from the above description.

It will thus be seen that there is provided a device in which the several objects of this invention are achieved, and which is well adapted to meet the conditions of practical use.

As various possible embodiments might be made of the above invention, and as various changes might be made in the embodiment set forth, it is to be understood that all matter herein set forth or shown in the accompanying drawing is to be interpreted as illustrative and not in a limiting sense.

Having thus described my invention, I claim as new and desire to secure by Letters Patent:—

1. In a shade of the character described, in combination, a tubular roller having an open end portion, a cap member secured to said roller at said open end portion, said cap having a cylindrical wall, and an end wall spaced from said portion, and one way speed responsive stop means housed within said cap member, said means comprising a plate mounted within said cap adjacent said end wall and having integral projections bent at right angles to the plane of said plate, pawls pivotally mounted on said projections, and a second plate secured to said roller and having openings slidably receiving the free end portions of said projections, said end wall retaining said end portions within said openings.

2. In a shade of the character described, in combination, a tubular roller having an open end portion, a cap member secured to said roller at said open portion, said cap having an apertured end wall spaced from said portion, a spindle extending within said roller, bearing means for said spindle within said cap member, and means for mounting said roller on a window frame secured to said spindle and extending thru said aperture, a ratchet plate non-rotatably mounted on said mounting means, said plate having a pair of diametrically disposed notches in the plane of said mounting means, and a plurality of pawls mounted within said cap member cooperating with said notches.

3. In a shade of the character described, in combination, a tubular roller having an

- open end portion, a cap member secured to said roller at said open portion, said cap having an apertured end wall spaced from said portion, a spindle extending within said 5 roller, bearing means for said spindle within said cap member, means for mounting said roller on a window frame secured to said spindle and extending thru said aperture, and speed responsive one-way brake means housed 10 within said cap member between said apertured wall and said bearing means, said last mentioned means comprising a plate adjacent the inner surface of the cap end wall, said plate having a plurality of spaced integral 15 projections bent away from said end wall, and dogs mounted on said projections. 20 4. In a shade of the character described, in combination, a tubular roller having an open end portion, a cap member secured to said roller at said open portion, said cap having an apertured end wall spaced from said portion, a spindle within said cap member, a member having non-circular cross-sections 25 for mounting said roller on a window frame secured to said spindle and extending thru said aperture, and speed responsive one-way brake means housed within said cap member between said apertured wall and said bearing means, said brake means comprising a ratchet 30 plate having a slot for receiving said mounting member, a plate member housed within said cap adjacent said end wall, and pawl members co-operating with said plate, pivotally mounted on said bearing means. 35 5. In a shade of the character described, in combination, a tubular roller having an open end portion, a cap member secured to said roller at said open portion, said cap having an apertured end wall spaced from said portion, a spindle extending within said roller, bearing means for said spindle within said cap member, means for mounting said roller on a window frame secured to said spindle and extending thru said aperture, and speed 40 responsive one-way brake means housed within said cap member between said apertured wall and said bearing means, said brake means comprising a ratchet plate, pawl members cooperating therewith, and a plate member positioned within said cap adjacent said apertured end wall, said plate having projections formed integral therewith and bent at right angles thereto to provide shafts for pivotally mounting said pawl members. 45 6. In a shade of the character described, in combination, a tubular roller having an open end portion, a cap member secured to said roller at said open portion, said cap having a cylindrical wall and an apertured end wall spaced from said portion, a spindle extending within said roller, a cup shaped member within said cap, said member having, bearing means for said spindle and a flange portion substantially contacting the inner surface of said cylindrical wall, means for 50 55 60 65 70 75 80 85 90 95 100 105 110 115 120 125 130
- mounting said roller on a window frame secured to said spindle and extending thru said aperture, and speed responsive one-way brake means housed within said cap member between said apertured wall and said bearing means, said brake means comprising a ratchet plate, pawl members cooperating therewith, and a plate member positioned within said flange and adjacent the apertured end wall of said cap member, said plate having projections formed integrally therewith and bent at right angles thereto, said bearing means having apertures to receive said projections, said projections pivotally mounting said pawl member. 75
7. In a shade roller of the character described, in combination, a tubular roller having an open end portion, a cap member secured to said roller on said end portion, said cap member having a cylindrical wall, and an apertured end wall spaced from said end portion, a spindle within said roller extending through the aperture in said end wall, a bearing member for said spindle within said cap secured to said roller and having a portion contacting the inner surface of said cylindrical wall, a plate mounted within said cap adjacent said end wall and having projections bent at right angles to the plane of said plate, said bearing member having openings for receiving the free end of said projections, and pawls pivotally mounted on said projections. 90 95
- In testimony whereof I affix my signature.
- AUGUST COPPOLA.
